ABSTRACT

A crane includes a base, an upperstructure rotationally mounted on the base, a boom, and a gantry. The boom is pivotally attached to the upperstructure at a front attachment location and supports a load line operable to raise a payload. The gantry is mounted on the upperstructure and supports a boom line coupled to the boom. The gantry includes at least one front leg mechanically coupled to the front attachment location and inclined away from the boom to apply, to the front attachment location, a horizontal force component towards the boom opposed by a horizontal force component applied by the boom towards the front leg. The upperstructure includes a frustoconical turret forming an upper circle and a lower circle. The front attachment location is aligned over the upper circle of the frustoconical turret.

FORCES UPON AN UPPERSTRUCTURE**

**CROSS REFERENCES TO RELATED
APPLICATIONS**

The present application is a continuation-in-part of application of U.S. patent application Ser. No. 15/083,173 filed Mar. 28, 2016, which claims the benefit of U.S. Provisional Application Ser. 62/140,346 filed Mar. 30, 2015 by Christopher Paul Chiasson entitled "Crane Having Effectively Coincident Gantry and Boom Forces Upon an Upperstructure" of which the full disclosures of these applications are incorporated herein by reference for all purposes.

FIELD

The present disclosure relates to a crane having a boom and a gantry mounted to an upperstructure rotationally mounted on a base.

BACKGROUND

A common form of crane has a base, an upperstructure rotationally mounted on the base, a boom having a proximal end pivotally attached to the upperstructure and having a distal end supporting a load line for raising a payload, and a gantry mounted on the upperstructure and having an upper end supporting a boom line coupled to the distal end of the boom for supporting the distal end of the boom. This common form of crane is often provided with a motor to swing the boom around the base, a boom hoist to raise or lower the inclination of the boom to align the distal end of the boom over the payload, and a load hoist to reel-in or reel-out the load line in order to raise or lower the payload.

The common form of crane introduced above is often used for pedestal mounted offshore cranes. An example is designated as a "Swing bearing mounted lattice boom wire luffed crane" in Figure 1 on page 2 of American Petroleum Institute Specification 2C, Offshore Pedestal Mounted Cranes, Seventh Edition, March 2012. In this example, the support base is a cylindrical pedestal, the upperstructure is generally rectangular, and the upperstructure is mounted to the pedestal via a swing-circle assembly for rotation about a vertical axis of the pedestal. The common gantry has a pair of rear legs mounted to the rear left and right of the upperstructure, and a pair of front legs mounted to the front left and right of the upperstructure, though different numbers of legs and different mounting positions for them do exist. The boom is a lattice boom pivotally connected to the front of the upperstructure. As a result, pedestal mounted offshore cranes typically use a four-legged gantry and six attachment locations on the upperstructure, including two attachment locations for a rear pair of gantry legs, two attachment locations for a front pair of gantry legs, and two attachment locations for a pair of boom legs at the proximal end of the boom. See, for example, Bonneson et al. U.S. Pat. No. 4,216,870 issued Aug. 12, 1980.

SUMMARY OF THE DISCLOSURE

The present disclosure describes a way of mounting a gantry and a boom to an upperstructure of a crane in order to reduce loading and bending moments upon the upperstructure and permit the upperstructure to have a reduced mass and a more compact size. The boom has a proximal end

pivotaly attached to the upperstructure at a front attachment location, and the gantry includes at least one front leg mechanically coupled to the front attachment location and inclined in a direction away from the boom to apply, to the 5 front attachment location, a horizontal force component towards the boom that is opposed by a horizontal force component from the boom towards the front leg. Therefore there is a large reduction in the net horizontal force applied from the front attachment location upon the upperstructure, 10 and consequently a reduced amount of structural mass is needed for reinforcing the front attachment location and strengthening the upperstructure to resist these forces, since the direction of the resultant forces are known to be mostly vertical.

15 Due to the reduction in the net horizontal force applied from the front attachment location of the boom to the upperstructure, the front attachment location can be brought closer to the center of the base of the crane, resulting in an additional reduction in the size and mass of the upperstructure. For a pedestal mounted crane, the upperstructure mass can be reduced further by using a circular turret as a primary component of the upperstructure, and locating the front attachment location on the circle of the turret.

In an arrangement, the front gantry leg provides a horizontal force component towards the boom that is equal and opposite to the horizontal force component from the boom towards the front gantry leg at the front attachment location. This can be true for all payloads and for all boom inclinations. The absence of any net horizontal force from the front attachment location to the upperstructure provides a minimum of force upon the upperstructure.

For example, the gantry can have four legs including a front pair of legs inclined in a direction away from the boom, and a vertical rear pair of legs, and each of the front legs can 25 be attached to the upperstructure at a respective front attachment location at which the boom is pivotally attached to the upperstructure. In this example, the rear pair of legs does not apply a horizontal force component to the upperstructure, and consequently the front pair of legs provides a horizontal 30 force component that is equal and opposite to the horizontal force component from the boom at the two front attachment locations. In this case, when the attachment locations for the rear legs are located on the rear of a circular turret, the horizontal force component and any bending moment from 35 the rear legs can also be eliminated. This leads to an arrangement in which a four-legged gantry has four attachment locations aligned over the circle of the turret, and the two front legs are attached to the upperstructure at the two front attachment locations of the boom. For example, the four attachment locations are located at the four corners of 40 a square circumscribed by the circle of the turret.

In an arrangement, the predictable downward force direction at all of the four attachment locations allows for further 45 optimization of the upperstructure by completely transforming its overall shape from rectangular to circular. The circular pattern allows for direct integration of additional components of the upperstructure (such as ball rings, which are circular due to their function) onto the turret without needing any transitioning structure, making the upperstructure 50 extremely mass-efficient. The circular shape of the upperstructure then gives the additional benefit of being naturally efficient at transmitting torque. When a crane is "twisted" due to a load being not underneath the distal end of the boom, or a strong wind, the upperstructure is what 55 resists this load. The commonly used rectangular shapes are not mass-efficient at resisting torque because they are prone to twist. Therefore, a large amount of internal stiffening and

support is required internal to most currently built upperstructures. However, transforming to a circular upperstructure means that the more efficient shape can resist the torsion without much additional bracing structure.

BRIEF DESCRIPTION OF THE DRAWINGS

Additional features and advantages of the present disclosure will be described below with reference to the drawings, in which:

FIG. 1 is a top view of a crane having effectively coincident gantry and boom forces upon an upperstructure;

FIG. 2 is a side view of the crane introduced in FIG. 1;

FIG. 3 is a top view of an assembly of a gantry and turret of the crane introduced in FIG. 1;

FIG. 4 is a side view of the assembly of FIG. 3;

FIG. 5 is a front view of the assembly of FIG. 3;

FIG. 6 is an oblique view of the assembly of FIG. 3;

FIG. 7 is an oblique view showing the proximal end of the boom pivotally connected to the assembly of FIG. 3;

FIG. 8 is a side view showing the boom in a position of maximum upward inclination with respect to the assembly of FIG. 3;

FIG. 9 is a side view of the assembly of FIG. 3 showing additional components attached to the turret;

FIG. 10 is a top section view of the assembly of FIG. 9 along line 10-10 in FIG. 9;

FIG. 11 is an expanded side view within a boundary line 11-11 in FIG. 9;

FIG. 12 is an expanded side view within a boundary line 12-12 in FIG. 9;

FIG. 13 is an oblique view of the assembly of FIG. 9;

FIG. 14 is another oblique view of the assembly of FIG. 9;

FIG. 15 is an oblique view of the assembly of FIG. 9 after the addition of optional cross bracing within the turret;

FIG. 16 is a front section view showing the shared connection of the left front gantry leg and the left leg of the proximal end of the boom to the upperstructure;

FIG. 17 is a front section view showing an alternative construction in which a left foot pin attaches both the left front gantry leg and the left leg of the boom to the upperstructure;

FIG. 18 is a front section view showing an alternative construction of a shared connection using a first foot pin for attaching a left front gantry leg to the upperstructure and a second foot pin for attaching a left boom leg the upperstructure;

FIG. 19 is a front section view showing an alternative construction of a front attachment location for a crane that has a single front gantry leg and both the single front gantry leg and the proximal end of the boom are attached to the upperstructure at this front attachment location;

FIG. 20 is a side view of another example of a crane;

FIG. 21 is a top view of an assembly of a gantry and turret of the crane introduced in FIG. 20;

FIG. 22 is a side view of the assembly of FIG. 21;

FIG. 23 is a front view of the assembly of FIG. 21; and

FIG. 24 is an oblique view of the assembly of FIG. 21.

While the disclosed subject matter is susceptible to various modifications and alternative forms, specific examples have been shown in the drawings and will be described in detail. It should be understood, however, that it is not intended to limit the disclosure to the particular forms shown, but on the contrary, the intention is to cover all

modifications, equivalents, and alternatives falling within the scope of the disclosure as defined by the appended claims.

DETAILED DESCRIPTION

It will be appreciated that for simplicity and clarity of illustration, where appropriate, reference numerals have been repeated among the different figures to indicate corresponding or analogous elements. In addition, while specific details are set forth in order to provide an understanding of the examples described herein, it will be appreciated by those skilled in the art that the examples described herein can be practiced without these specific details. In other instances, methods, procedures and components have not been described in detail so as not to obscure the related relevant feature being described. Also, the description is not to be considered as limiting the scope of the examples described herein. The drawings are not necessarily to scale and the proportions of certain parts may be exaggerated to better illustrate details and features of the present disclosure.

Several definitions that apply throughout this disclosure will now be presented. The term "coupled" is defined as connected, whether directly or indirectly through intervening components, and is not necessarily limited to physical connections. The connection can be such that the objects are permanently connected or releasably connected. The terms "comprising," "including" and "having" are used interchangeably in this disclosure. The terms "comprising," "including" and "having" mean to include, but not necessarily be limited to the things so described.

FIGS. 1 and 2 show a crane 20. In general, the crane 20 includes a base (21 in FIG. 2), an upperstructure 22 rotationally mounted on the base 21, a boom 23 having a proximal end 24 pivotally attached to the upperstructure and having a distal end (25 in FIG. 2) supporting a load line (26 in FIG. 2) for raising a payload (27 in FIG. 2), and a gantry 28 mounted on the upperstructure and having an upper end 29 supporting a boom line (30 in FIG. 2) coupling the gantry 28 to the distal end of the boom. The crane 20 also has a boom hoist 31 for reeling in or reeling out the boom line 30 to raise or lower the inclination of the boom 23 to align the distal end 25 of the boom over the payload 27, and a main load hoist 32 to reel-in or reel-out the load line 26 in order to raise or lower the payload.

In the example of FIGS. 1 and 2, a main load block (33 in FIG. 2) having a hook (34 in FIG. 2) is used for mechanically coupling the load line 26 to the payload 27. A two-part reeving of the load line 26 mechanically couples the load block 33 to the distal end 25 of the boom 23, and the payload 27 is hung from the hook 34. In a similar fashion, a two-part reeving of the boom line 30 mechanically couples the upper end 29 of the gantry 28 to the distal end 25 of the boom.

The crane 20 in FIGS. 1 and 2 is more specifically an example of a pedestal-mounted offshore crane having a lattice boom 23. The base 21 can be a cylindrical pedestal, and the upperstructure 22 is rotationally mounted to the pedestal via a swing-circle assembly (35 in FIG. 2).

FIG. 20 illustrates an example of a crane 20 which can be, for example, deployed on a structure 10, such as a ship or an offshore structure. In other examples, the crane 20 can be deployed on land. The base 21 can be a cylindrical pedestal, similar to the base 21 in FIGS. 1 and 2. In some examples, the base 21 can be a rectangular prism, frustoconical, and/or any other suitable shape to support and withstand the forces from the crane 20.

In at least one example, as illustrated in FIGS. 20-24, one or more legs 210 can extend vertically from the surface of the structure 10. The legs 210 can be coupled with the surface of the structure 10 such that the legs 210 are stable and can withstand the forces from the crane 20. As illustrated in FIGS. 20-24, the legs 210 can be substantially cylindrical. In other examples, the legs 210 can have a cross-section with a shape that is substantially circular, oval, rectangular, triangular, or any other suitable shape.

The base 21 can be positioned about the leg 210 such that the leg 210 extends vertically through the base 21. The base 21 can then be coupled with the surface of the structure 10. The upperstructure 22 can also be positioned about the leg 210. For example, the upperstructure 22 can be positioned on above, and/or coupled with, the base 21.

Relative directional terms such as above, below, upper, and lower are in relation to a gravity vector direction G. For example, the upperstructure 22 being positioned above the base 21 means that, in the gravity vector direction G, the order of the components is the upperstructure 22 and then the base 21. Similarly for upper and lower, in the gravity vector direction G, the order of the components is the upper component and then the lower component.

The swing circle assembly 35 selectively rotates the upperstructure 22 about a central vertical axis 36 of the pedestal 21, in order to swing the boom 23 around the pedestal. For example, the swing-circle assembly 35 has a circular array of hydraulic motors (121 to 128 in FIG. 10) mounted to the upperstructure 22, and each hydraulic motor has a pinion that meshes with a common internal gear mounted to the pedestal 21. A swing-circle assembly having such a gearing arrangement is well known, and details are found in Bonneson et al. U.S. Pat. No. 4,216,870 issued Aug. 12, 1980.

A diesel engine 37 is mounted on the rear end of the upperstructure 22 to drive a hydraulic pump 38 for powering the hydraulic motors in the swing-circle assembly 35. The hydraulic pump 37 also powers a hydraulic motor in the boom hoist 31, and a hydraulic motor in the main load hoist 32. An operator's cab 39 is mounted on the right side of the upperstructure 22. The operator's cab 39 includes manual controls for controlling the hydraulic motors to the lift the payload 27 from an initial location and to deposit the payload at a desired final location.

In the example of FIGS. 1, 2, and 20, the boom hoist 31 is mounted on the upperstructure 22 just to the rear of the gantry 28. In an alternative construction, the boom hoist 32 could be mounted on a pad (113 in FIGS. 9, 11, and 13-15) between the feet of the rear legs of the gantry 28. The main moist 32 is mounted to the boom 23 near the proximal end 24 of the boom.

For handling light-weight payloads, the distal end 25 of boom 23 can carry a jib (41 in FIGS. 2 and 20) supporting an auxiliary load block (42 in FIGS. 2 and 20). A two-part reeving of an auxiliary load line (43 in FIGS. 2 and 20) suspends the auxiliary load block 42 from the jib 41. An auxiliary load hoist 44 reels-in and reels-out the auxiliary load line 43 in order to raise or lower a light-weight payload (not shown) suspended from a hook on the auxiliary load block 42.

Although the primary purpose of the gantry 28 is for supporting the boom line 30, FIG. 2 shows a number of components mounted to the gantry for secondary functions. A boom stop 51 is mounted to the gantry 28 for abutting against the boom 23 when the boom reaches a maximum upward inclination. Ladders 52, 53 and platforms 54, 55 are mounted to the gantry 28 for the convenience of maintenance personnel.

Horizontal jibs 56, 57, 58 are mounted to the gantry 28 for lifting, removing, and replacing components that may need service. A horizontal jib 56 is provided for servicing of the boom hoist 31. An extendable horizontal jib 57 is provided for servicing the diesel engine 37. A horizontal jib 58 is provided for servicing the main and auxiliary load hoists 32, 44.

It is desired to attach the gantry 28 and the boom 23 to the upperstructure 22 in such a way that boom forces are effectively coincident with gantry forces so that the forces upon the upperstructure from the boom are minimized. In the example of FIGS. 1, 2, and 20, this is done by sharing the locations of attachment of the proximal end 24 of the boom 23 on the upperstructure with two respective locations of attachment of an inclined front pair of legs of the gantry 28 on the upperstructure.

FIGS. 3-7 and 21-24 show details of a left front location of attachment 87 and a right front location of attachment 88 on a turret 60 of the upperstructure. The front pair of gantry legs includes a left front leg 61 and a right front leg 62. A foot 81 of the left front leg 61 stands on the left front attachment location 87, and the left front attachment location 87 receives a left foot pin 103 for pivotally attaching a left leg (101 in FIG. 7) of the boom 23 to the upperstructure. The foot 81 is aligned with the left foot pin 103. A foot 82 of the right front leg 62 stands on the right front attachment location 88, and the right front attachment location 88 receives a right foot pin 61 for pivotally attaching a right leg (102) of the boom 23 to the upperstructure.

The pair of front legs 61, 62 of the gantry 28 extends from the two respective front attachment locations 87, 88 on the upperstructure 22 to the upper end 29 of the gantry 28, and the proximal end 24 of the boom 23 is attached to the upperstructure 22 at the two respective front attachment locations, and the pair of front legs is inclined in a direction away from the boom 23 to apply, to each of the two respective front attachment locations, a horizontal force component towards the boom that is canceled by a horizontal force component applied by the boom towards the pair of front legs. The horizontal force component applied by the pair of front legs 61, 62 is seen in FIG. 2 to arise from tension in the boom cable 30, which pulls the upper part 29 of the gantry 28 towards the distal end 25 of the boom. Movement of the upper part 29 of the gantry 28 in the horizontal direction towards the distal end of the boom is resisted by an axial compression force in the front legs 61, 62. Due to the inclination of the front legs 61, 62 away from the boom 23, this axial compression force has a horizontal force component towards the boom, and this horizontal force component is proportional to the axial compression force and the sine of the angle of deviation of the pair of front legs 61, 62 from vertical.

Moreover, in the example of FIGS. 1-8 and 20-24, the gantry 28 has a rear pair of legs 63, 64, and the rear pair of legs is vertical in comparison to the font pair of legs which is inclined backwards. Therefore, the rear pair of legs 63, 64 does not apply any significant horizontal force to the upperstructure 22, and the rear pair of legs 63, 67 applies a vertical upward force upon the upperstructure 22. Consequently, the horizontal component of the force applied by the boom 23 upon the foot pins 103, 61 is balanced by an opposing horizontal component of force applied by the pair of front legs 67, 68 of the gantry 28 upon the two front attachment locations 87, 88. Therefore the two front attachment locations do not transmit any significant horizontal force to the upperstructure 22, and the net force is downward in a vertical direction. This further minimizes the forces upon the

upperstructure from the boom, and further minimizes bending or torsion at all four locations **87, 88, 76, 77** where the four gantry legs **61, 62, 63, 64** are attached to the upperstructure **20**.

FIGS. 3-6 and 21-24 show further details of the gantry **28** and its attachment to the turret **60** of the upperstructure. The two front legs **61, 62**, are similar to each other, and the two rear legs **63, 64** are similar to each other. Each rear leg **63, 64** is a straight cylindrical steel tube. Each front leg **61, 62** is an elongated steel assembly including a respective straight upper tubular section **65, 66** and a respective straight lower section **67, 68**. Each straight lower section **67, 68** is comprised of a pair of parallel spaced steel beams **69, 70** and **71, 72**. The lower sections **67, 68** of the front leg **61, 62** are parallel to each other. The upper sections **65, 66** of the front legs are not parallel to each other and instead taper towards each other for a minimal spacing at the upper end **29** of the gantry **28**. The lower section **67** of the left front leg **61** has a longitudinal axis that is aligned with the left front foot pin **103**, and the lower section **68** of the right-front leg **62** has a longitudinal axis that is aligned with the right front foot pin **61**.

The spacing between the two parallel spaced beams in each pair of parallel spaced beams **69, 70** and **71, 72** provides a clearance fit with a respective leg of the proximal end of the boom, so that an upper and rearward portion of the respective leg of the proximal end of the boom is received between the two parallel spaced beams when the boom is at a maximum upward inclination (as shown in FIG. 8). For example, each parallel spaced steel beam has an "I" or "T" shaped-cross section, and the head of the "I" or "T" of one beam in each pair faces the head of the "I" or "T" of the other beam in the pair.

The turret **60**, as illustrated in FIGS. 1-8, is a primary cylindrical component of the upperstructure (**22** in FIG. 2). The base of the turret **60** is configured to sit upon the top of the pedestal base (**21** in FIG. 2) in coaxial alignment with the vertical axis (**36** in FIG. 2) of the pedestal base. The swing-circle assembly (**35** in FIG. 2) rotationally couples the base of the turret **60** with the top of the pedestal base (**21** in FIG. 2) so that any torsional moments upon the turret about the vertical axis (**36** in FIG. 2) are transmitted to the pedestal base. Such bending moments arise during normal operation of the crane due to the lifting of the payload (**27** in FIG. 2).

Each rear leg **63, 64** of the gantry **28** has a respective foot **73, 74** that is a steel pad-eye plate, and the upper parts of the two feet **73, 74** are joined by a horizontal steel beam **75**. Each of the two feet **73, 74** are received between a respective pair **76, 77** of parallel-spaced vertical steel pad-eye plates welded onto the turret **60**, and a respective foot pin **78, 79** attaches the respective foot **73, 74** to the turret **60** via the respective pair **76, 77** of pad-eye plates welded to the turret. Thus, the turret **60** is an efficient circular barrel-like structure that spreads out point-like contact forces of the boom and gantry before these forces are applied to bearing elements of the swing-circle assembly (**35** in FIG. 2).

FIGS. 21-24 illustrate an example of a turret **60**, which has a frustoconical shape. The frustoconical turret **60** forms an upper circle **602** and a lower circle **604**. The upper circle **602** has a diameter **602D**, and the lower circle **604** has a diameter **604D**. The diameters **602D, 604D** are influenced by economics of production for taller upperstructures **22**, and by structural feasibility for short upperstructures **22**. For example, for taller upperstructures **22**, the diameters **602D, 604D** of the upper circle **602** and the lower circle **604** may not cause a steep wall slope, but the upperstructure **22** may become larger and thus more expensive. For shorter upper-

structures **22**, the diameters **602D, 604D** of the upper circle **602** and the lower circle **604** may cause a steep wall slope, as the upperstructure **22** may become a near-flat dish and thus structurally infeasible.

5 In at least one example, for example as illustrated in FIGS. 20-24, the diameter **602D** of the upper circle **602** is larger than the diameter **604D** of the lower circle **604**. In other examples, the diameter **602D** of the upper circle **602** can be smaller than the diameter **604D** of the lower circle **604**. The frustoconical turret **60** is oriented such that the upper circle **602** is above the lower circle **604** in relation to the gravity vector direction **G**. When the frustoconical turret **60** is positioned on the base **21**, the lower circle **604** is adjacent to the base **21**.

10 Similar to FIGS. 1-8, the swing-circle assembly **35** rotationally couples the lower circle **604** of the turret **60** with the top of the pedestal base **21** so that any torsional moments upon the turret **60** about the vertical axis (**36** in FIG. 20) are transmitted to the pedestal base **21**. In at least one example, 15 the crane **20** may disengage its slewing brakes as the crane **22** is about to pick up a load. During such action, the torsion on the upperstructure **22** may not be resisted by the pedestal base **21** to allow the crane **20** to automatically align the boom **23** over the load **27**. The ring bearings of the swing-circle assembly **35** (illustrated in FIG. 10) are coupled with the lower circle **604** of the frustoconical turret **60**, as the lower circle **604** functions as the base of the turret **60**. Such bending moments arise during normal operation of the crane due to the lifting of the payload (**27** in FIG. 20). In at least 20 one example, moments or torques about the vertical axis may be of lower importance to overturning moments. Overturning moments can be classified as primary or secondary. Primary overturning moments attempt to topple the crane **20** forward (about an axis parallel to the boom heel pins). 25 Secondary overturning moments attempt to topple the crane **22** sideways left or right.

20 The frustoconical shape of the turret **60**, as illustrated in FIGS. 21-24, provides for a smaller swing-circle assembly **35** in relation to the weight capacity of the crane **20**. 25 Additionally, in at least one example, the shape of the turret **60** can provide for a smaller swing-circle assembly **35** in relation to the size of the non-rotating obstructions the crane **20** should avoid, such as the legs **210** of a liftboat. For example, if the turret is cylindrical, a greater weight capacity 30 requires a larger diameter of the turret and corresponding ring bearing (illustrated in FIG. 10) in the swing-circle assembly **35**. The cost of ring bearings as the diameter increases is not linearly proportional. As the diameter of the ring bearing increases, the cost increases at a greater rate. 35 With a frustoconical turret **60**, the weight capacity of the crane **20** may require a larger upperstructure, but the diameter of the ring bearing can be smaller. Similar to the turret **60** in FIGS. 2-8, the circular shape of the upper circle **602** of the frustoconical turret **60** spreads out the point-like 40 contact forces of the boom and gantry before the forces are applied to the bearings of the swing-circle assembly **35**. The larger upper circle **602** provides for the larger upperstructure connection, but the lower circle **604** and the corresponding swing-circle assembly **35** and ring bearings can have a 45 smaller diameter **604D** than the upper circle **602**. The forces enacted on the upper circle **602** are distributed through the frustoconical turret **60** such that ring bearings with a smaller diameter can be utilized, thereby saving cost.

45 Each front leg **61, 62** has a respective foot **81, 82** including a respective steel plate (**83, 84, 85, 86** in FIGS. 6 and 24) welded to the bottom end of each beam **69, 70, 71, 72** so as to be perpendicular to the longitudinal axis of each

beam. Each front leg 61, 62 stands on a respective mount 87, 88 welded onto the turret 60. Each mount 87, 88 includes a respective pair of parallel-spaced vertical steel pad-eye plates (91, 92, 93, 94 in FIGS. 6 and 24) welded onto the turret 60, and a respective inclined steel plate (95, 96, 97, 98 in FIGS. 6 and 24) welded perpendicular to each of the pad-eye plates (91, 92, 93, 94 in FIGS. 6 and 24) so as to be parallel to and aligned with a matching plate on the foot of the neighboring front leg 61, 62. The foot of each front leg is attached to the turret 60 by fastening the matching plates together, for example by welding around the outer neighboring edges of the matching plates, or by bolting the matching plates together.

A pair of parallel-spaced steel beams 99, 100 is disposed within the turret 60 to brace the gantry leg mount locations on the turret 60. While the disclosure discusses the beams 99, 100 as steel beams, in some examples, the beams 99, 100 can be made of other metals, alloys, polymers, or any other suitable material. A left beam 99 has a front end welded to the internal surface of the turret 60 just below the left front mount 87, and a rear end welded to the internal surface of the turret 60 just below the left rear mount 76. A right beam 100 has a front end welded to the internal surface of the turret 60 just below the right front mount 88, and a rear end welded to the internal surface of the turret 60 just below the right rear mount 77. As illustrated in FIG. 24, the beams 99, 100 assist in redirecting the vertical load diagonally down the frustoconical turret 60. Accordingly, the vertical load is distributed through the turret 60.

FIG. 7 shows the proximal end 24 of the boom 23 attached to the turret 60 at the front mounts 87, 88. The proximal end 24 of the boom 23 includes a left leg 101 and a right leg 102. A left foot pin 103 secures a left foot of the left leg 101 in the left front mount 87, and a right foot pin 61 secures a right foot of the right leg 102 in the right front mount 88. Each front gantry leg 61, 62 carries a compressive force having a line of action passing through a pivot axis 200 of the boom 23 at the respective front attachment location 87, 88. The line of action is the longitudinal axis of the lower portion 67, 68 of the front gantry leg 61, 62. The pivot axis 200 of the boom 23 extends from the left foot pin 103 to the right foot pin 61. The left and right foot pins 103, 61 are coaxial with the pivot axis 200 of the boom 23, so that longitudinal axis of the left front foot pin 103 is the pivot axis 200, and the longitudinal axis of the right foot pin 61 is also the pivot axis 200.

FIG. 8 shows the boom 23 in a position of maximum upward inclination. In this case the upper and rear part of the left leg 101 of the boom 23 is received between the beams 69 and 70 of the left front gantry leg 61, and the upper and rear part of the right leg 102 of the boom 23 is received between the beams 71 and 72 of the right front gantry leg 62. So as not to interfere with the beams 70 and 71, the first upper lateral (i.e., right-to-left) brace (107 in FIG. 7) of the boom 23 is further from the proximal end 24 of the boom 23 than the first lower lateral brace (106 in FIG. 7) of the boom.

FIGS. 9, 10, 11, 12, 13, 14, and 15 show some additional components mounted to the turret 60. An engine support structure 110 is mounted on the rear of the turret 60. A cab support structure 111 is mounted on the right side of the turret 60. These structures are made of steel beams welded to each other or welded to the turret 60. As shown in FIGS. 10 and 13 to 15, a hydraulic motor mounting structure 112 is disposed within the turret 60 and welded to the turret. As shown in FIGS. 9, 11, and 13 to 15, a boom hoist mounting pad 113 is welded to the beam 75 between the rear legs 63, 64 of the gantry.

FIG. 10 shows that the front attachment locations 87, 88 (for the gantry front leg and the legs of the boom) and also the rear attachment locations 78, 79 (for the gantry rear legs) are each aligned over the circle of the turret 60. As shown in FIGS. 21-24, with a frustoconical turret 60, the front attachment locations 87, 88 (for the gantry front leg and the legs of the boom) and also the rear attachment locations 78, 79 (for the gantry rear legs) are each aligned over the upper circle 602 of the turret 60. In addition, the attachment locations 87, 88, 78, 79 are located at respective corners of a square. In other examples, the attachment locations 87, 88, 78, 79 may be located at respective corners of a rectangle or other cyclic quadrilateral. FIG. 10 also shows that the hydraulic motor mounting structure 112 mounts a circular array of hydraulic motors 122, 123, 124, 125, 126, 127, 128 shown in dashed line representation. Each of the hydraulic motors drives a respective pinion that meshes with a common internal ring gear mounted to the pedestal (21 in FIG. 2). The respective pinion is coaxial with a central vertical axis of each gearbox, and the respective pinion is located at the bottom of each motor. In at least one example, gear boxes with eccentricity may be utilized such that the respective pinion can be parallel with the central vertical axis of each gearbox. The common internal ring gear is coaxial with the vertical axis (36 in FIG. 2) of the pedestal (21 in FIG. 2). Therefore, the hydraulic motors can be powered to selectively rotate the turret 60 about the vertical axis of the pedestal in order to swing the boom (23 in FIG. 2) around the pedestal.

As shown in FIG. 15, optional cross beams 114, 115 have been added to further strengthen the turret 60. This permits the turret 60 to be used in a crane having an increased load capacity in comparison to a crane that would not use the cross beams 114, 115.

FIGS. 16 to 19 show alternative constructions for front attachment locations. In each of these examples, a front gantry leg, which is inclined in a direction away from the boom, is mechanically coupled to the front attachment location of the boom so that the front gantry leg applies, to the front attachment location, a horizontal force component towards the boom that is opposed by a horizontal force component applied by the boom towards the front leg.

FIG. 16 shows a front section view of the left front attachment location 87. As described above, the foot 81 of the left front gantry leg includes a pair of inclined steel plates 83, 84 attached to respective ones of the parallel spaced beams 69, 70. The left front attachment location 87 includes a pair of vertical parallel spaced steel plates 91, 92 welded to the turret 60 over the circle of the turret, and a pair of inclined steel plates 95, 96 welded to respective ones of the vertical parallel spaced steel plates 91, 92. The inclined steel plates 83, 84 on the foot 81 of the left front gantry leg rest upon and are attached to respective ones of the inclined steel plates 95, 96 on the left front attachment location 87. The left leg 101 on the proximal end of the boom is received between the beams 69, 70 and the plates 83, 84 and 95, 96 and 91, 92. The left front foot pin 103 pivotally attaches the left leg 101 of the boom to the vertical steel plates 91, 92 of the left front attachment location 87.

FIG. 17 shows an alternative construction in which a left foot pin 129 attaches both a left front gantry leg and the left leg 101 of the boom to the upperstructure. In this example, the lower portion of the left front gantry leg still includes a pair of parallel spaced steel beams 121, 122 so that the left leg 101 of the boom can be received between the parallel spaced steel beams 121, 122 when the boom has a maximum upward inclination. The foot of the left front gantry leg also

11

has a pair of inclined steel plates 123, 124 welded to the ends of respective ones of the parallel spaced steel beams 121, 122. In addition, parallel spaced steel pad-eye plates 131, 132 are welded to the ends of respective ones of the parallel spaced steel beams 121, 122. The pad-eye plates 131, 132 are received between a pair of vertical parallel spaced steel plates 127, 128 welded to the turret 60. Two inclined steel plates 125, 126 are welded on top of respective ones of the vertical parallel spaced steel plates 127, 128 so that the inclined plates 123, 124 on the foot of the left front gantry leg may rest upon respective ones of the inclined plates 125, 126 during assembly of the gantry onto the upperstructure. The inclined plates 123, 124, 125, and 126 could be omitted without loss of function by using jacks to load or unload the gantry from the left foot pin 129. The foot of the boom left leg 101 is received between the parallel spaced steel pad-eye plates 131, 132. The single left foot pin 129 pivotally attaches the left leg 101 of the boom to the upperstructure and also attaches the left front leg of the gantry to the upperstructure by passing through the eyes of the pad-eye plates 131, 132.

FIG. 18 is a front section view of an alternative construction for a shared connection of a left front gantry leg 141 and a left boom leg 140 to the upperstructure. In this example, the shared connection includes a first foot pin 153 for attaching the left front gantry leg 141 to the upperstructure and a second foot pin 149 for pivotally attaching the left boom leg 140 to the upperstructure. The foot of the left front gantry leg 141 includes a pair of inclined steel plates 143, 144 welded to the bottom of the left front gantry leg 141, which is a cylindrical steel tube. Two parallel spaced steel pad-eye plates 131, 132 are also welded to the bottom of the left front gantry leg 141. The pad-eye plates 131, 132 are received between a pair of parallel-spaced vertical steel plates 147, 148 welded to the turret 60. Two inclined steel plates 145, 146 are welded on top of respective ones of the vertical steel plates 147, 148. The inclined plates 143, 144 welded to the bottom of the left front gantry leg 141 rest upon respective ones of the inclined plates 145, 146 during assembly of the gantry onto the upperstructure. The inclined plates 143, 144, 145, and 146 could be omitted, and then the bottom of the gantry leg 141 could rest on the top of each of the vertical plates 147, 148 during assembly of the gantry onto the upperstructure. The first foot pin 153 passes through the vertical steel plates 147, 148 and the eyes of the pad-eye plates 131, 132 to attach the left front gantry leg 141 to the upperstructure. The second foot pin 149 passes through the vertical steel plates 147, 148 and the foot of the left leg 140 of the boom to pivotally attach the left leg 140 of the boom to the upperstructure.

FIG. 19 is a front section view showing an alternative construction of a front attachment location for a crane that has a single front gantry leg and both the single front gantry leg and the proximal end of the boom are attached to the upperstructure at this front attachment location. This alternative construction is derived from the construction in FIG. 7 by moving the two front gantry legs (61, 62 in FIG. 7) towards each other over the circle of the turret 60 until the two front gantry legs merge into a single front gantry leg having three parallel-spaced steel beams 161, 162, 163. In this example, the outer steel beams 161, 163 each have a "T" shaped cross section, and the middle steel beam 162 has an "I" shaped cross section. The proximal end of the boom still has a left leg 176 and a right leg 177 but these two legs 176, 177 are closer together.

In FIG. 19, the left leg 176 of the boom is received between a first pair of parallel spaced vertical steel plates

12

170, 171 welded to the turret 60. The right leg 177 of the boom is received between a second pair of parallel spaced vertical steel plates 172, 173 welded to the turret. An inclined steel plate 178 is welded on top of the vertical plate 170. An inclined steel plate 179 is welded on top of the vertical plates 171 and 172. An inclined steel plate 180 is welded on top of the vertical plate 173. An inclined steel plate 181 is welded on the bottom of the beam 161. An inclined steel plate 182 is welded on the bottom of the beam 162. An inclined steel plate 183 is welded on the bottom of the beam 163. The inclined steel plates 181, 182, 183 rest upon and are attached to the inclined steel plates 178, 179, 180 during assembly of the gantry onto the upperstructure. For example, the inclined steel plates 181, 182, 183 are welded or bolted to the inclined steel plates 178, 179, 180 during assembly. A single foot pin 174 passes through the legs 176, 177 of the boom and through the vertical steel plates 170, 171, 172, 173 to pivotally attach the legs 176, 177 of the boom to the upperstructure.

The alternative connections in FIGS. 16 to 19 have bilateral symmetry in their front views as shown. However, in some situations, it may be desirable to have asymmetrical connections. One example is a mounting of an undersized boom to the upperstructure of a crane having a turret and a four-leg gantry as described above. The undersized boom may have two legs that are spaced from each other by a distance shorter than the distance between the feet of the two front gantry legs. In this case, for example, the foot of the left front gantry leg would not be centered over the foot of the left leg of the boom, and the foot of the right front gantry leg would not be centered over the foot of the right leg of the boom, and instead the foot of the left front gantry leg would be offset towards the left of the crane, and the foot of the right front gantry leg would be offset towards the right of the crane.

The disclosures shown and described above are only examples. Even though numerous characteristics and advantages of the present technology have been set forth in the foregoing description, together with details of the structure and function of the present disclosure, the disclosure is illustrative only, and changes may be made in the detail, especially in matters of shape, size and arrangement of the parts within the principles of the present disclosure to the full extent indicated by the broad general meaning of the terms used in the attached claims. It will therefore be appreciated that the examples described above may be modified within the scope of the appended claims.

What is claimed is:

1. A crane comprising:

a base;

an upperstructure rotationally mounted on the base; a boom having a proximal end pivotally attached to the upperstructure at a front attachment location and having a distal end supporting a load line operable to raise a payload; and

a gantry mounted on the upperstructure and having an upper end supporting a boom line coupled to the distal end of the boom operable to support the distal end of the boom;

wherein the gantry includes at least one front leg mechanically coupled to the front attachment location and inclined in a direction away from the boom to apply, to the front attachment location, a horizontal force component towards the boom that is opposed by a horizontal force component applied by the boom towards the front leg; and

13

wherein the upperstructure includes a frustoconical turret forming an upper circle and a lower circle, and the front attachment location is aligned over the upper circle of the frustoconical turret.

2. The crane as claimed in claim 1, wherein a diameter of the upper circle is larger than a diameter of the lower circle.

3. The crane as claimed in claim 1, wherein the base includes a pedestal coupled with the upperstructure, the upperstructure includes a swing circle assembly coupling the upperstructure to the pedestal to be operable to rotate the upperstructure about a vertical axis of the pedestal.

4. The crane as claimed in claim 3, wherein the swing circle assembly includes a ring bearing coupled with the lower circle of the turret.

5. The crane as claimed in claim 1, wherein a leg extends vertically through the base, and wherein the upperstructure is positioned about the leg.

6. The crane as claimed in claim 1, wherein the at least one front leg extends from the front attachment location to the upper end of the gantry.

7. The crane as claimed in claim 1, wherein the horizontal force component applied by the front leg towards the boom is equal to the horizontal force component applied by the boom towards the front leg.

8. The crane as claimed in claim 1, wherein the front leg carries a compressive force having a line of action passing through a pivot axis of the boom.

9. The crane as claimed in claim 8, wherein the pivot axis of the boom is a longitudinal axis of a foot pin pivotally attaching the proximate end of the boom to the upperstructure.

10. The crane as claimed in claim 1, which further includes a foot pin pivotally attaching the proximate end of the boom to the upperstructure at the front attachment location, and the foot pin also attaches the front leg of the gantry to the upperstructure at the front attachment location.

11. The crane as claimed in claim 1, wherein the gantry includes a left front leg and a right front leg, the left front leg extends from a left front attachment location on the upperstructure to the upper end of the gantry, and the right front leg extends from a right front attachment location on the upperstructure to the upper end of the gantry.

12. The crane as claimed in claim 11, wherein the left front attachment location is aligned over the upper circle of the turret, and the right front attachment location is aligned over the upper circle of the turret.

13. The crane as claimed in claim 11, wherein the upperstructure includes a pair of parallel spaced vertical plates at each of the left front and the right front attachment locations, and the proximal end of the boom includes a pair of legs, and a foot of each of the pair of legs of the boom is disposed between the parallel spaced vertical plates at a respective one of the left front and the right front attachment locations, and a respective foot pin attaches the foot of each of the legs

14

of the boom to the parallel spaced vertical plates at the respective one of the left front and the right front attachment locations.

14. The crane as claimed in claim 13, wherein a foot of each of the left front leg and the right front leg of the gantry is secured on top of the parallel spaced plates at a respective one of the left front and the right front attachment locations.

15. The crane as claimed in claim 14, wherein each of the left front leg and the right front leg includes a pair of parallel spaced beams extending upward from a respective one of the left front and the right front attachment locations, and an upper and rearward portion of a respective leg of the boom is receivable between the pair of parallel spaced beams in each pair of parallel spaced beams when the boom is at a maximum upward inclination.

16. A crane comprising:

a base; and

an upperstructure operable to be rotationally mounted on the base, the upperstructure including a frustoconical turret forming an upper circle and a lower circle, wherein the lower circle is adjacent to the base.

17. The crane of claim 16, wherein a diameter of the upper circle being larger than a diameter of the lower circle.

18. The crane as claimed in claim 16, wherein the upperstructure includes a swing circle assembly coupling the upperstructure to the base operable to rotate the upperstructure about a vertical axis of the base.

19. The crane as claimed in claim 18, wherein the swing circle assembly includes a ring bearing coupled with the lower circle of the frustoconical turret.

20. The crane as claimed in claim 16, wherein a leg extends vertically through the base; wherein the upperstructure is positioned about the leg.

21. The crane as claimed in claim 16, wherein a front attachment location of the upperstructure to pivotally attach a proximal end of a boom is aligned over the upper circle of the frustoconical turret.

22. The crane as claimed in claim 21, further comprising a boom pivotally coupled with the upperstructure; and a gantry including at least one front leg mechanically coupled to the front attachment location and inclined in a direction away from the boom to apply, to the front attachment location, a horizontal force component towards the boom that is opposed by a horizontal force component applied by the boom towards the front leg.

23. The crane as claimed in claim 22, wherein the horizontal force component applied by the front leg towards the boom is equal to the horizontal force component applied by the boom towards the front leg.

24. The crane as claimed in claim 22, wherein the at least one front leg extends from the front attachment location to an upper end of the gantry.

* * * * *
